UNITED STATES PATENT OFFICE.

LESTER P. BARLOW, OF CLEVELAND, OHIO.

THERMOSTATIC REGULATING DEVICE.

Application filed February 28, 1923, Serial No. 621,844. Renewed July 30, 1924.

To all whom it may concern:

Be it known that I, LESTER P. BARLOW, whose residence is Cleveland, county of Cuyahoga, and State of Ohio, and a citizen 5 of the United States, have invented certain new and useful Improvements in Thermo- static Regulating Devices, of which the following is a specification, reference being had to the accompanying drawing, forming a 10 part thereof.

My invention relates to thermostatic devices for regulating a valve controlling the flow of fluid such for instance as the supply of water to a steam generating boiler, and 15 my invention has for its object to provide a construction and arrangement of a chamber enclosing the expansion member of a thermostatic device by which steam entering the chamber will be condensed to an 20 extent sufficient to ensure a relatively rapid flow of steam thereto. A further object of my invention is to provide an expansion member which will be particularly sensitive to changes in temperature and a further object 25 of the invention is to provide means for adjusting the position of the valve controlled by the expansion member by which a nicety of adjustment not heretofore possible may be readily obtained.

With the objects above indicated and other objects hereinafter described in view my invention consists in the construction and combination of elements hereinafter described and claimed.

Referring to the drawings:

Figure 1 is a longitudinal central sectional view of a thermostatic water supply regulating device embodying my invention.

Figure 2 is a detail end view of the valve.

Figure 3 is a side view of a steam boiler having my water supply regulating device applied thereto.

Figure 4 is a front view of the same.

In the drawings 1 indicates a steam generating boiler from which steam for power or other purposes may be taken by pipe 2. 45 3 indicates a condensing chamber consisting of a horizontal arranged tube arranged at approximately the height at which it is 50 desired to maintain the level of the water in the boiler 1, outside the boiler and at such distance from the side of the boiler that it will be aircooled sufficiently to cause 55 steam from the boiler to condense to a greater or less extent. This condensing

chamber 3 is connected on its upper side by tube 4 with a vertical tube 5 which is connected at its upper end by horizontal tube 6 with the interior of the boiler above the normal water level and preferably, as 60 shown, near the upper end of the boiler, and is connected at its lower end by horizontal tube 7 with the interior of the boiler below the normal water level and preferably near its lower end. The portion of the tube 4 65 which is connected with vertical tube 5 is preferably horizontal as shown.

The condensing chamber 3 is connected on its lower side by tube 8 with the vertical tube 5 towards its lower end. 70

Steam carrying with it more or less water, that is wet steam, will enter the tube 6 and, as it passes down the vertical tube 5, the water carried with the steam will tend to separate and pass directly down the tube 75 and only comparatively dry steam will enter the tube 4 and, passing through this tube, will enter the condensing chamber 3. This chamber being at a distance from the boiler and cooled by air circulation, the steam entering it will be in large measure condensed so reducing the pressure in the chamber as to give the effect of a partial vacuum and drawing in steam through tube 4 until the pressure in the chamber approximates the 80 boiler pressure. The water of condensation from the chamber flows down tube 8 to vertical tube 5 and back through tube 7 to the boiler.

By reason of this condensing of the 90 steam in the chamber the flow of steam into the chamber will be very much greater than if the chamber were less cool.

Within the tube 3 is arranged the expansion member 10 of the thermostatic device 95 for regulating a valve 24 by which the passage of water or other fluid through a pipe 12 may be regulated. In the construction shown the pipe 12 is connected with the water supply of the boiler and the valve 100 is arranged to control a by-pass by which water in excess of that required to maintain the water in the boiler at a predetermined level is returned to the source of supply by an arrangement commonly employed in 105 connection with boiler feeding means and not necessary to be here shown.

The expansion member 10 consists of a relatively long tube of brass or other metal having a relatively high coefficient of ex- 110

10 pansion having numerous perforations 13 along its length and having one end fixedly secured to the reduced end 14 of a plug 15 which is secured in the end of the chamber 3. As shown this plug is secured in the end of the chamber by screwthreads and the expansion member is secured on the reduced portion 14 by screwthreads.

15 The interior diameter of the chamber 3 is considerably greater than the extreme diameter of the tubular expansion member 10 so that the steam may circulate freely about the exterior of the expansion member and the perforations 13 permit the steam to enter the interior of the expansion member so as to heat it both exteriorly and interiorly.

20 At the end opposite to that which is secured to the plug 15 the expansion member is provided with a head 16 from which extends a rod 17 which extends through an opening in the end of the chamber 3 and is surrounded by a packing gland 18 of any usual construction preferably protected by a cap 19 through the head of which the rod 25 17 extends.

25 The outer end of the rod 17 is bored out and interiorly screwthreaded to receive a screwthreaded nipple 20 on the end of a rod 21 which extends through a packing gland 22 into a valve chamber 23 and carries on its end a valve 24 which is adapted to seat against valve seat 25 in a horizontal passage 26 extending into the valve chamber in line with the rod 21. The outer end of 30 this passage 26 is connected with the water inlet pipe 12 and from the valve chamber 23 a discharge or return pipe 28 leads at right angles to the direction of the horizontal passage 26.

35 The valve 24 is preferably provided with in the passage 26 with radial guides 29 to prevent chattering.

40 The valve chamber 23 is provided with oppositely extending arms 30 and 31 provided with openings through which extend adjusting rods 32 and 33 respectively. The end portions of these rods are screwthreaded as shown and are provided respectively with nuts 34 and 35 against which the arms 30 and 31 bear on one side and with nuts 36 and 37 respectively between which and the arms 30 and 31 are arranged coiled springs 38 and 39. Lock nuts 40 and 41 respectively serve to hold nuts 36 and 37 against movement.

45 At their other ends the adjusting rods 32 and 33 are secured in a disk or head 42. From the plug 15 a screwthreaded rod 43 extends rearward through a central opening 50 in the disk or head 42. On this rod 43 is carried in rear of the disk or head a nut 44 formed in the hub of a hand wheel 45 having a flange 46 in which are formed, at suitable distances apart, a series of holes 47. 55 Carried by the disk or head 42 is a bracket

60 having a hole 49 through it in the line of the holes 47 so that a pin 50 thrust through the hole 49 may enter one of the holes 47 and lock the hand wheel against rotation. By withdrawing the pin 50 and rotating the hand wheel 45 in one direction the hub of which bearing against the disk or head 42, the rod 43 will be drawn rearward drawing with it the expansion member 10 and, through the connections above described, drawing the valve 24 away from the valve seat 25. When the hand wheel 45 is rotated in the other direction it permits the rod 43 to be moved forward, this forward movement being effected by a nut 51 formed in the hub of a hand wheel 52 on the forward side of the disk or head 42. By this forward movement of the rod 43 the expansion member 10 is caused to move the valve 24 towards the valve seat 25. The nut 51 serves, when forced against the disk or head 42, to cooperate with the nut 44 to lock the rod 43, and with it the valve 24, in adjusted position.

65 The screwthread on the rod 43 is relatively fine so that rotation of the nuts 44 and 51 even through a complete rotation will effect only a slight movement of the rod and rotation through the arc represented by the distance between adjacent holes 47 will effect only an extremely slight movement thus permitting an adjustment of micrometric character.

70 By adjustment of the nuts 34 and 36 on rod 32 and nuts 35 and 37 on rod 33 the position of the valve chamber 23 and the valve seat 25 relative to the valve 24 may be adjusted with considerable accuracy. When so adjusted to substantially the position required the final and exact adjustment 75 is effected by means of the nuts 44 and 51. In this way a nicety of adjustment may be secured which would not be possible by the adjustment of the valve chamber on the adjusting rods 32 and 33.

75 The hand wheels 45 and 52 being at the end away from the valve chamber are readily accessible. All that is necessary is to remove the pin 50, and rotate the hand wheel 45 through such arc as may be required, and again insert the pin, the hand wheel 52 being of course suitably rotated to permit the rearward movement of the rod 43 or to cause its forward movement as permitted by the rotation of the hand wheel 45.

80 Instead of the holes 47 and pin 50 any other device for holding the hand wheel in adjustment position and adapted to be released to permit its rotation may be used.

85 In arranging the device the tube 4 should be connected with the condensing chamber near one end, preferably the end towards the valve chamber, and the tube 8 should be connected with the condensing chamber near

its other end so that the steam will pass from one end of the condensing chamber to the other.

While the invention is described with particular reference to its use as a means for regulating a valve for controlling the water supply for a steam generating boiler it is to be understood that it is not limited to controlling a valve for any particular purpose as the valve controlled by it may be a throttle valve or a valve for controlling fuel supply or for any other purpose it being essential to the operation of the device only that steam be supplied to the outer chamber.

Having thus described my invention what I claim is:

1. In a thermostatic device for regulating a valve, an outer chamber of tubular form and an expansion member within the outer chamber consisting of a tube closed at both ends and perforated between its ends to admit the heating medium to its interior, having its outer end fixedly secured to the outer end of the chamber and having at its inner end a head carrying a rod extending through the inner end wall of the outer chamber and connected to the valve to be regulated.

2. In a thermostatic device for regulating a valve, an outer chamber and an expansion member within the outer chamber consisting of a tube closed at both ends and perforated between its ends to admit the heating medium to its interior, fixedly secured at its outer end to the outer end of the outer chamber and provided at its inner end with a rod extending through the inner end wall of the outer chamber, a valve connected with said rod, a valve chamber having a seat for the valve, and means for adjusting the outer chamber with reference to the valve chamber.

3. In a thermostatic device for regulating a valve, an outer chamber and an expansion member within the outer chamber fixedly secured at its outer end in the outer end of the outer chamber and provided at its inner end with a rod extending through the inner end wall of the outer chamber, a valve connected with said rod, a valve chamber having a seat for the valve and means for adjusting the outer chamber with reference to the valve chamber comprising a head at the outer end of the outer chamber, a rearwardly extending rod carried by the outer end of the outer chamber extending through said head, and means on said rearwardly extending rod adapted to engage said head.

4. In a thermostatic device for regulating a valve, an outer chamber and an expansion member within the outer chamber fixedly secured at its outer end within the outer chamber and provided at its inner end

with a rod extending through the inner end wall of the outer chamber, a valve connected with said rod, a valve chamber having a seat for the valve, and means for adjusting the outer chamber with reference to the valve chamber comprising a head at the rear of the outer chamber, a rearwardly extending screwthreaded rod carried by the outer end of the outer chamber extending through said head, and a nut engaging the screwthreaded rod and bearing against said head.

5. In a thermostatic device for regulating a valve, an outer chamber and an expansion member within the outer chamber fixedly secured at its outer end in the outer end of the outer chamber and provided at its inner end with a rod extending through the inner end wall of the outer chamber, a valve connected with said rod, a valve chamber having a seat for the valve, and means for adjusting the outer chamber with reference to the valve chamber comprising a head at the rear of the outer chamber, a rearwardly extending screwthreaded rod carried by the outer chamber extending through said head, and nuts engaging the screwthreaded rod and bearing against said head.

6. In a thermostatic device for regulating a valve, an outer chamber and an expansion member within the outer chamber fixedly secured at its outer end in the outer end of the outer chamber and provided at its inner end with a rod extending through the inner end wall of the outer chamber, a valve connected with said rod, a valve chamber having a seat for the valve, and means for adjusting the outer chamber with reference to the valve chamber comprising a head at the rear of the outer chamber, a rearwardly extending screwthreaded rod carried by the outer chamber extending through said head, and a nut engaging the screwthreaded rod and bearing against said head, and means for locking said nut against rotation.

7. In a thermostatic device for regulating a valve, an outer chamber and an expansion member within the outer chamber secured at one end within the outer chamber and provided at its other end with a rod extending through the wall of the outer chamber, a valve connected with said rod, a valve chamber having a seat for the valve, and means for adjusting the outer chamber with reference to the valve chamber comprising a head at the rear of the outer chamber, a rearwardly extending screwthreaded rod carried by the outer chamber extending through said head, and a nut engaging the screwthreaded rod and bearing against said head, a hand wheel carrying said nut and means carried by the head for engaging the hand wheel to lock the nut against rotation.

8. In a thermostatic device for regulating a valve, an outer chamber and an expansion member within the outer chamber secured at its outer end in the outer end of the outer chamber and provided at its inner end with a rod extending through the inner end wall of the outer chamber, a valve connected with said rod, a valve chamber having a seat for the valve, and means for adjusting the outer chamber with reference to the valve chamber comprising a head at the rear of the outer chamber and rods connecting said head with the valve chamber, and means for adjusting the outer member with reference to said head, comprising a rearwardly extending screwthreaded rod carried by the outer chamber extending through said head, and a nut engaging the screwthreaded rod and bearing against said head.

10. In a thermostatic device for regulating a valve, an outer chamber and an expansion member within the outer chamber secured at one end within the outer chamber and provided at its other end with a rod extending through the wall of the outer chamber, a valve connected with said rod, a valve chamber having a seat for the valve, and means for adjusting the outer chamber with reference to the valve chamber comprising a head at the rear of the outer chamber, rods connecting said head with the valve chamber, means for adjusting the outer member with reference to said head, comprising a rearwardly extending screwthreaded rod carried by the outer chamber extending through said head, a nut engaging the screwthreaded rod and bearing against said head.

15. In a thermostatic device for regulating a valve, an outer chamber and an expansion member within the outer chamber fixedly secured at its outer end in the outer end of the outer chamber and provided at its inner end with a rod extending through the inner end wall of the outer chamber, a valve connected with said rod, a valve chamber having a seat for the valve, and means for adjusting the outer chamber with reference to the valve chamber comprising a head at the rear of the outer chamber, rods connecting said head with the valve chamber, means for adjusting the outer member with reference to said head, comprising a rearwardly extending screwthreaded rod carried by the outer chamber extending through said head, a nut engaging the screwthreaded rod and bearing against said head, a hand wheel carrying said nut and means for locking said hand wheel against rotation.

20. In a thermostatic device for regulating a valve, an outer chamber and an expansion member within the outer chamber fixedly secured at its outer end in the outer end of the outer chamber and provided at its inner end with a rod extending through the inner end wall of the outer chamber, a valve connected with said rod, a valve chamber having a seat for the valve, and means for adjusting the outer chamber with reference to the valve chamber, comprising a head at the rear of the outer chamber, rods connecting said head with the valve chamber, means for adjusting the outer member with reference to said head, comprising a rearwardly extending screwthreaded rod carried by the outer chamber extending through said head, a nut engaging the screwthreaded rod and bearing against said head, a hand wheel carrying said nut and means for locking said hand wheel against rotation.

25. In a thermostatic device for regulating a valve, an outer chamber and an expansion member within the outer chamber secured at its outer end in the outer end of the outer chamber and provided at its inner end with a rod extending through the inner end wall of the outer chamber, a valve connected with said rod, a valve chamber having a seat for the valve, and means for adjusting the outer chamber with reference to the valve chamber, comprising a head at the rear of the outer chamber, rods connecting said head with the valve chamber, means for adjusting the outer member with reference to said head, comprising a rearwardly extending screwthreaded rod carried by the outer chamber extending through said head, a nut engaging the screwthreaded rod and bearing against said head, a hand wheel carrying said nut and means for locking said hand wheel against rotation.

30. In a thermostatic device for regulating a valve, an outer chamber and an expansion member within the outer chamber secured at its outer end in the outer end of the outer chamber and provided at its inner end with a rod extending through the inner end wall of the outer chamber, a valve connected with said rod, a valve chamber having a seat for the valve, and means for adjusting the outer chamber with reference to the valve chamber, comprising a head at the rear of the outer chamber, rods connecting said head with the valve chamber, means for adjusting the outer member with reference to said head, comprising a rearwardly extending screwthreaded rod carried by the outer chamber extending through said head, a nut engaging the screwthreaded rod and bearing against said head, a hand wheel carrying said nut and means for locking said hand wheel against rotation.
